HARLAND FANKBONER, OF CHICAGO, ILLINOIS, ASSIGNOR TO THE GOSS PRINTING PRESS COMPANY, A CORPORATION OF ILLINOIS

GRIPPING MECHANISM

Application filed June 13, 1929. Serial No. 370,618.

The present invention relates to novel and useful improvements in gripper mechanism and more particularly gripper mechanism for the cylinders of printing presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention in the novel parts, construction, arrangements, combinations and improvements is herein shown and described.

The accompanying drawings, referred to herein and constituting a part hereof, illustrate one embodiment of the invention, and together with the description, serve to explain the principles of the invention.

Of the drawings:

Fig. 1 is a fragmentary, vertical section through a cylinder to which the improved gripper mechanism is applied.

Fig. 2 is a fragmentary elevational view taken in the plane of line 2—2 of Fig. 1.

Fig. 3 is a section taken on the line 3—3 of Fig. 1.

The invention is directed to providing an improved gripper mechanism in connection with the cylinders of printing presses by means of which a sheet, fed to the cylinder, may be gripped with substantially uniform pressure by all the grippers on the cylinder without nicely adjusting the grippers on their supporting shaft. The invention is further directed to provide a gripper mechanism in which the difficulties heretofore caused by the torsional movement of the gripper supporting and actuating shaft are substantially eliminated. The present invention also provides a gripper mechanism which will grip the sheet or sheets fed to it with substantially uniform pressure regardless of the number of sheets fed to the cylinder.

Heretofore it has been customary to employ a relatively stiff and rigid gripper finger cooperating with a solid relatively rigid gripper pad on the cylinder. With this construction, however, as the grippers are turned to grip the sheet or sheets fed to the cylinder

the supporting and actuating shaft is subjected to torsional strains which causes the grippers to be displaced relative to each other. Generally eight or ten such gripper fingers are mounted on each shaft and it is very difficult to adjust these grippers so that they will simultaneously grip the sheet. Also, once the grippers have been so adjusted, they get out of adjustment in a very short time, thereby causing some of the gripper fingers to bear very hard against the cylinder while others of the fingers do not touch the cylinder. These and other difficulties are avoided by the present invention.

It will be understood that the foregoing general description and the following detailed description as well, are exemplary and explanatory of the invention but are not restrictive thereof.

Referring now in detail to the present preferred embodiment of the invention, the gripper mechanism is shown as applied to, and used in connection with a printing press cylinder 10, in the gap which is provided an operating shaft 11 for the gripper fingers.

As embodied, the gripper mechanism comprises a plurality of resilient gripper fingers 13 mounted on the actuating and supporting shaft 11, by means of which they are moved to grip a sheet, or group of sheets 14, between them and the surface of the cylinder 10. Preferably, each of the fingers 13 is formed of a relatively thin, flat spring and at its outer end 16 is bent substantially in conformity with the shape of the cylinder 10.

Means are provided for mounting and supporting the gripper fingers on the actuating shaft and, as embodied, split collars 17 are spaced along the actuating shaft 11 and clamped thereon by means of bolts 18 which can be tightened to firmly clamp the collars on the shaft. The fingers are curved around the collars 17 at rear portion of the fingers and are provided with a hole at their inner end 20 to fit over the bolts 18 and be held fast to the collar by means of bolt heads 21. By thus securing the fingers at their rear, or inner, ends and bending them around the collars, a relatively long finger having a high degree of resiliency can be provided with

out making the gripper mechanism abnormally bulky. Each of the resilient fingers 13 is preferably supported by a separate collar 17 and by loosening the bolts 18, the collars can be turned on the shaft 11, thereby 5 moving the fingers 13 with them. In this manner all the fingers can be adjusted to simultaneously grip the sheet on the cylinder. In case the fingers do not simultaneously grip 10 the sheet on the cylinder, the fingers first to grip the sheet will yield and allow the remaining fingers to press on the sheet thereby firmly holding it.

Means are provided for initially tensioning 15 the fingers, thereby allowing each of the resilient fingers to exert a relatively heavy pressure on the sheet as soon as the fingers touch the sheet, and these means comprise stops for preventing free movement of the fingers 13 when they are not in contact with 20 the sheets on the cylinder. As embodied, collars 17 are formed with channels 23 substantially diametrically opposite the finger-securing bolt heads 21, and a pin 24 is held 25 in the sides 25 of each channel 23, thereby retaining the resilient fingers under the desired degree of tension and within its proper channel, and at the same time allowing, to a considerable degree, a further tensioning of 30 the resilient fingers as they are pressed against the sheet on the cylinder.

The gripper fingers are preferably adjusted 35 for normal operation, as shown in Figure 1, so that in sheet-gripping position each of the fingers 13 will be slightly spaced from 40 the retaining pins 24, giving a substantially uniform tension for a wide variation in thickness of the group of sheets carried on the cylinder.

45 The invention in its broader aspects is not limited to the specific mechanisms shown and described but departures may be made therefrom within the scope of the accompanying claims without departing from the principles of the invention and without sacrificing its chief advantages.

What I claim is:—

1. In combination, a cylinder, and a sheet gripping device mounted thereon, and comprising 50 a shaft journaled in the cylinder, a long flexible gripper mounted on the shaft and extending past the shaft to gripping position for a sheet on the cylinder, and means mounted on the shaft but spaced apart from the gripper finger mounting for imposing 55 initial tension on the gripper finger.

2. In combination, a cylinder, and a sheet gripping device mounted thereon, and comprising 60 a shaft journaled in the cylinder, a long flexible gripper mounted on the shaft and extending past the shaft to gripping position for a sheet on the cylinder, and means mounted on the opposite side of the shaft from the gripper finger mounting for placing 65 the gripper finger under initial tension.

3. In combination, a cylinder, a gripper shaft journaled in the cylinder, a collar rotatable about and fixable to the shaft, a flexible gripper finger mounted on the collar, and a tension imposing stop for the gripper finger 70 on the opposite side of the collar from the gripper finger mounting.

4. In combination a cylinder, a gripper shaft journaled in the cylinder, a flexible gripper finger, means for imposing an initial tension on the gripper finger, a collar rotatable about and fixable to the shaft whereby the final tension of the gripper finger 75 against the cylinder may be varied by rotation of the collar about the shaft.

In testimony whereof, I have signed my name to this specification.

HARLAND FANKBONER.
